(57) **CLAIM**

We claim the ornamental design for an emitter part, as shown and described.

DESCRIPTION

FIG. 1 is a perspective view of the emitter part in accordance with our new design;

FIG. 2 is a top plan view of the emitter part of FIG. 1;

FIG. 3 is a bottom view of the emitter part of FIGS. 1-2; FIG. 4 is a rear elevation view of the emitter part of FIGS. 1-3;

FIG. 5 is a front elevation view of the emitter part of FIGS. 1-4;

FIG. 6 is a right side elevation view of the emitter part of FIGS. 1-5; and,

FIG. 7 is a left side elevation view of the emitter part of FIGS. 1-6.

The broken lines in the figures are for the purpose of illustrating portions of the emitter part and form no part of the claimed design.
